J. M. KELLEY.

PUMP.

APPLICATION FILED AUG. 30, 1918.

Patented Oct. 11, 1921.

UNITED STATES PATENT OFFICE.

JOHN M. KELLEY, OF ROCHESTER, NEW YORK.

PUMP.

1,393,138.

Specification of Letters Patent. Patented Oct. 11, 1921.

Original application filed April 8, 1918, Serial No. 227,368. Divided and this application filed August 30, 1918. Serial No. 252,108.

To all whom it may concern:

Be it known that I, JOHN M. KELLEY, a citizen of the United States, and resident of Rochester, in the county of Monroe and 5 State of New York, have invented certain new and useful Improvements in Pumps, of which the following is a specification.

The present invention relates to pumps, the illustrated construction being designed 10 for holding a fire extinguishing liquid within the cylinder in rear of the piston until such time that it is desired to use the liquid, when the piston is drawn outwardly causing the liquid to flow in front of the piston 15 through a passageway in the piston for ejection when the piston is moved in the opposite direction. This application is a division of an application filed by me on April 8, 1918, Serial No. 227,368.

An object of this invention is to provide 20 a piston loosely mounted on the piston rod, and provided with a passageway which, when the piston rod is moved outwardly, will be opened, due to the fact that the piston is retarded by frictional engagement 25 with the cylinder walls, and will be closed when the piston rod is moved inwardly, due to the same cause. A further object of the invention is to provide an adjustable relief 30 passage in the piston permitting a part of the liquid to flow to the rear of the piston, so that a movement of the piston may take place, notwithstanding the restricted size of the discharge opening as compared with the 35 pressure area of the piston. Still another object of the invention is to provide means for admitting air to the rear face of the piston, as the latter moves inwardly, this means being entirely closed while the piston 40 is in its innermost position, so that, when the device is not in use, there will be no danger of leakage through the air inlet passage. A still further object of the invention is to provide an improved air compressing 45 chamber associated with the discharge passage of the fire extinguisher to prevent sputtering due to the varying pressure on the piston. A still further object of the invention is to provide an air compressing 50 chamber which is so constructed that it will not collect any of the liquid passing from the discharge orifice, and at the same time will be housed by the cylinder.

To these and other ends the invention consists of certain parts and combinations of

parts, all of which will be hereinafter described, the novel features being pointed out in the appended claims.

In the drawings:

Figure 1 is an axial section through a fire extinguisher constructed in accordance with the present invention;

Fig. 2 is a detail view showing the inlet end of the air inlet passage open;

Fig. 3 is a detail sectional view, showing the piston shifted on a piston rod in such a manner as to open the passageway;

Fig. 4 is an enlarged detail view of the adjustable relief passage;

Fig. 5 is a detail view of the upper face of the piston; and

Fig. 6 is an enlarged detail view of the discharge passage.

Referring more particularly to the drawings, 1 indicates the open-ended tubular member of the cylinder, which also embodies a head 2 provided with a packing gland 3 and a filling opening closed by a plug 4. The cylinder also embodies a head 5 provided with a discharge passage which, in this instance, is formed by a tube 6 extending through a chamber 7 in the head 5 and having a restricted portion 6^a and a relatively wider portion 6^b. This chamber 7, in this instance, incloses an air compressing chamber 8 which is in the form of a long narrow tube coiled about the tube 6 with one end closed and the other end opening at 9 to the wider portion 6^b of the discharge passage in the tube 6. It is apparent that any liquid flowing through the discharge passage under pressure will compress the air in the chamber 8, and this compression reacts on the liquid in such a manner as to cause such liquid to flow from the pump in a steady stream, thus preventing any sputtering due to an uneven pressure on the piston. Owing to the fact that the air compression chamber 8 is in the form of a coiled tube, it is impossible for any liquid passing through the discharge passageway to flow into the air compression chamber to any great extent, and by far the greater advantage attained by this form of chamber is that no matter in what position or angle at which the pump is discharged the compression chamber will perform its function equally well.

The piston, in this instance, embodies a metal plate 10, against which a ring 11 of

packing material, such as felt, rests, said ring being centered by a ring-shaped member 12 abutting the plate 10 within the packing ring 11. The packing ring may be held 5 to the plate 10 by a plate 13 which has a plurality of laterally-bent fingers 14 at its edges, said fingers centering the ring 12 and also engaging and overhanging the packing ring 11, thus acting on the ring not only to 10 hold it to the plate 10, but to expand such ring, due to the fact that the fingers 14 are of spring material. Eyelets 15 may pass through the plates 13 and 10 to secure them together, and at the same time serve to provide 15 passageways 16, other passageways being provided by registering openings in both plates so that an annular series of passageways is formed. The spring fingers 14 are also adapted to engage with an annular 20 spreading device 17 formed on the head 5 to coöperate with the fingers in such a manner as to move them outwardly in order to press the packing ring 11 firmly against the walls of the cylinder 1, thus preventing the 25 passage of liquid past the packing ring. The construction of this piston is claimed in my aforesaid application #227,368, filed April 8, 1918.

The piston has a slight movement on the 30 piston rod between a disk 18 on the rod and a nut 19 on said rod. This movement is provided in order that when the piston rod is moved outwardly the piston, owing to its frictional contact with the side walls of the 35 cylinder, will not move until the nut 19 co-operates with it, and in this way the annular seat 20 which surrounds the passageways 16 will move out of coöperation with the disk 18, thus permitting the fluid or liquid 40 which is stored within the cylinder 1 above the piston to flow to the inner or under side of the piston. When the piston is moved in the opposite direction, this frictional contact between the piston and the cylinder 45 walls will hold the piston until such time that the disk 18 co-operates with the annular seat 20, thus closing the passageway and permitting the liquid to be forced by the piston through the discharge tube 6. While 50 the piston is in its innermost or lower position, the passageway 16 may be closed, and this closing may be effected by a tapered end 21 of an extension on the piston rod coöperating with the seat 22 in the discharge 55 passageway, said seat being positioned on the inner side of the end 9 of the air compression chamber. The piston rod extension may be also screw-threaded at 23 in order that the nut 19 may be fitted thereon, 60 and also that the interior threaded walls of the tube 6 may be engaged to lock the piston in its innermost position, where its packing ring 11 is forced outwardly against the walls of the cylinder by the spreader 17.

65 It is desirable to admit air into the cylin-

der in rear of the piston, as the latter moves forwardly or toward the discharge orifice. Heretofore an air inlet has been provided in the cylinder head, but it has been found that the valve which closes the air inlet will accidentally become opened, thus permitting the escape of the liquid contained in the cylinder above the head. To prevent this wasting of the liquid there is provided an air inlet which will be positively closed when 70 the piston is in its innermost position, and the liquid is in the cylinder above the piston. To secure these results, the piston rod may be formed by a tube 24 working through the packing gland 3 and having a knob 25 at 75 its outer end. The inner end of this tube 24 is screw-threaded and engages with the internally-threaded walls of a chamber 26 formed in a casting 27, which carries the disk 18 and the screw-threaded portion 23. 80 This chamber 26 has a port 28 opening to the cylinder, while the tubular rod 24 has a port 29 which, when the rod is in the position shown in Fig. 1, lies within the packing gland 3 so that the air inlet passage is 85 closed to the interior of the cylinder. When the rod is withdrawn this port 29 is carried beyond the packing gland and permits 90 the entrance of air by way of the tube 24 and the port 28. A ball valve 30 is situated 95 within the chamber 26 and seats against the lower end of the tube 24, being held to the seat by a helical spring 31 within the chamber. This ball valve prevents the liquid being discharged through the tube 24 when the piston is moved from the position shown in 100 Fig. 1, to cause the liquid to flow to the under side of the piston.

It has been found that in a device of this character where a large piston is provided with a small discharge orifice or outlet from the cylinder, the movement of the piston is very slow, and to increase the speed of the piston a relief passage 32 is provided in the piston. In this instance, this relief passage 105 is formed by a slot in a screw 33 which is adjustably mounted in the piston plate 10, so that the size of the relief passage may be varied in order to secure the most effective action.

In the use of the invention, the parts are adjusted to the positions shown in Fig. 1, and the filling plug 4 being removed, the fire extinguisher fluid, such as carbon-tetrachlorid, is introduced into the cylinder above 120 the piston, after which the plug 4 is fitted in the filling opening and the extinguisher is ready for use. When it is desired to use the extinguisher, the piston rod is turned so as to disengage the screw-threaded project- 125 ing end from the walls of the discharge tube 6, thus opening the discharge passageway. After the piston rod has been disengaged from the tube 6, it is pulled outwardly, thus causing the piston to move on the rod, due 130

to the frictional engagement between the packing ring 11 and the interior walls of the cylinder 1, thus opening the passageways 16. Further movement of the piston rod will cause the piston to travel toward the upper or rear end of the cylinder, thus causing the liquid to flow to the opposite face of the piston. After the piston has been moved to the limits of its movement, the piston rod is forced in the opposite direction, thus bringing the disk 18 against the ring 20 and closing the passageways 16, so that the force of the piston acts on the liquid and ejects it from the cylinder through the discharge tube 6. The pressure on the liquid causes a compression of the air in the air compression tube 8, and this compressed air chamber tends to maintain a steady flow of the liquid from the discharge tube notwithstanding an unequal pressure on the piston. During the movement of the piston, a small amount of the liquid travels through the relief passage 32 and prevents the choking action in the discharge orifice 6. When the piston is in its innermost position, the packing 11 is held in firm engagement with the walls of the cylinder by the spreading ring 17 which acts on the spring arms or fingers 14 to force the packing ring 11 outwardly. The liquid in the chamber 1 is, during the nonuse of the extinguisher, held from leakage by way of the air inlet port which relieves the vacuum on the upper face of the piston.

From the foregoing it will be seen that there has been provided a pump in which the piston has a movement on the piston rod to permit the fluid to flow from one side thereof to the other in order to pass out of the discharge passage. A packing ring is provided which dispenses with the cupped piston, and yet firmly cooperates with the walls of the cylinder. Leakage of the fluid in the cylinder is prevented by providing the air intake passage in the piston rod, and moving the intake end of the passage to a position where it will be closed. A compression chamber is provided which maintains a steady flow from the discharge passage, and yet does not collect any material amount of the liquid in any position in which the extinguisher is held.

What I claim as my invention and desire to secure by Letters Patent is:—

1. A pump comprising a cylinder provided with a discharge passage having a restricted portion, a piston operating in said cylinder, means for closing the discharge passage, and an air compression chamber leading from said discharge passage between the closed portion of the said passage and the restricted portion.

2. A pump comprising a cylinder having a head provided with a discharge passage having a restricted portion, a piston operating in the cylinder, a piston rod for operating the piston, means carried with the rod for closing the discharge passage, and an air-compression chamber inclosed by the head and leading from the discharge passage between the closed portion and the restricted portion.

3. A pump comprising a cylinder having a discharge passage having a restricted portion, a piston operating in the cylinder, means for closing the discharge passage, and a coiled air compression chamber communicating with the discharge passage between the closed portion and the restricted portion.

4. A pump comprising a cylinder having a hollow head with a discharge tube projecting therein and provided with a seat and a restricted portion, a piston operating in the cylinder, means carried by the piston for co-operating with the seat to close the discharge tube, and an air compression chamber coiled about the discharge tube in the head and communicating with the discharge tube between the seat and the restricted portion.

5. In a pump, a cylinder having a packing gland in one head and a discharge opening in its opposite head, a piston operating in the cylinder, and a tubular piston rod having an inlet and a discharge port, the inlet being so situated that it is closed by the packing gland when the piston rod is moved to innermost position.

6. In a pump, a cylinder having a packing gland in one head, a piston operating in the cylinder, a piston rod comprising a part to which the piston is secured formed with a valve chamber having a lateral discharge port and also a tube having its inner end engaging the inner wall of said chamber and forming a valve seat, said tube being provided with an inlet port which will be closed by the packing gland when the piston is moved to an inner position, and a ball valve in the chamber.

7. A pump of the type embodying a cylinder formed with a discharge opening, and a piston operating in the cylinder to force the liquid through the discharge opening and provided with a valved passageway by which the liquid may flow from one side of the piston to the other when the piston is moved away from the discharge opening, distinguished by an adjustable relief passageway in the piston which will permit the liquid to flow in the reverse direction through the piston when the latter is moved toward the discharge opening.

JOHN M. KELLEY.
